UNITED STATES PATENT OFFICE.

EDWARD H. T. LIVEING, OF QUEEN ANNE STREET, CAVENDISH SQUARE,
COUNTY OF MIDDLESEX, ENGLAND, ASSIGNOR TO JAMES JOSEPH
HICKS, OF SAME PLACE.

SPIRIT-THERMOMETER.

SPECIFICATION forming part of Letters Patent No. 251,371, dated December 27, 1881.

Application filed August 31, 1881. (No model.) Patented in England September 29, 1880.

To all whom it may concern:

Be it known that I, EDWARD HENRY TOR-
LESSE LIVEING, a subject of the Queen of
Great Britain, residing at Queen Anne Street,
5 Cavendish Square, in the county of Middlesex,
England, have invented certain new and use-
ful Improvements in Thermometers, (for which
I have received Letters Patent in England,
No. 3,939, dated September 29, 1880,) of which
10 the following is a specification.

The invention has for its object improve-
ments in thermometers, and relates to means
whereby greater distinctness in reading and a
novel and more ornamental appearance are ob-
15 tained than in thermometers of the description
heretofore in use. For this purpose, instead
of supplying the tube with mercury or with
spirit colored as heretofore, I supply it with
20 alcohol colored with a body known to chem-
ists as "fluorescine," with the addition of a
small quantity of some alkali, and I employ in
combination with the same a black or other
very dark background.

In order that my said invention may be more
25 clearly understood and readily carried into ef-
fect, I will proceed more fully to describe the
method of carrying the same into effect, refer-
ring to the accompanying drawing, which rep-
resents a front view of my improved ther-
30 mometer.

A is a thermometer-back; B, the tube, hav-
ing a dark or black background, b; and C, the
spirit within the tube, colored with fluorescine
and alkali, so as to present a translucent am-
35 ber-colored appearance in the bulb portion c
and an opaque deep-green-colored appear-
ance to the column portion c'.

The fluorescine (which may be obtained from
chemical dealers under that name) is to be dis-
40 solved in the alcohol (the strength of which is
not important, and methylated spirit of com-
merce answers well) in the proportion of about
one-third of a grain to the fluid ounce of spirit.
This proportion can, however, be varied con-
45 siderably without much alteration in effect.
The liquid thus produced is scarcely at all flu-
orescent, but on the addition of a small quan-
tity of an alkali it becomes intensely so. For
this purpose I employ strong ammonia solu-
50 tion, in the proportion of one drop to the fluid
ounce of spirit; but other alkalies may be used
and the exact proportion is not at all mate-
rial. The fluid thus obtained is introduced

into the thermometer-tubes in the usual man-
ner, these tubes being preferably made with 55
bulbs of various ornamental forms, such as
spiral, helical, or any other form that may be
found convenient; but no form is here claimed,
the object of such bulbs being to display to
the best advantage the double color possessed 60
by the fluid, which reflects a green light but
transmits a yellow light. Tubes thus made
and supplied with the colored fluid above de-
scribed are, according to my invention, to be
mounted against a black or other very dark 65
colored scale (with white figures) as a dark
background for the fluid; or the dark back-
ground may be produced by varnishing the
back of the tube with black or other very dark
colored varnish, or by a band of black or other 70
very dark enamel drawn within the glass of
the tube or on the back thereof, in place of the
ordinary white enamel used for this purpose.

If the thermometer be intended for a reg-
istering one, the index or needles must be 75
made of some reflecting material in order to
show within the fluorescent fluid. In place of
those of black glass commonly employed, I
find white enamel-glass answers well for this
purpose.

Having thus described the nature of my said
invention and the mode in which I carry the
same into effect, I would have it understood
that what I claim is—

1. An indicator-tube having its contained 85
spirit colored with fluorescine and alkali, as set
forth.

2. A thermometer provided with a tube hav-
ing its contained spirit colored with fluorescine
and alkali, as set forth.

3. A thermometer-tube having a dark back-
ground and its contained spirit colored with
fluorescine and alkali, as and for the purpose
set forth.

4. A thermometer constructed with a back, 95
A, tube B, dark background b, and a spirit
filling, C, adapted to present a translucent
amber-colored appearance to the bulb portion
c and an opaque deep-green-colored appear-
ance to the column portion c', as set forth.

EDWARD H. T. LIVEING.
